AUTOMOBILE HOOD ORNAMENT

Henry J. Keane, Grosse Pointe, Mich., assignor
to Chrysler Corporation, Highland Park, Mich.,
a corporation of Delaware

Application June 11, 1952, Serial No. 20,124

Term of patent 7 years

(Cl. D14—18)

To all whom it may concern:

Be it known that I, Henry J. Keane, a citizen of the United States, residing in the city of Grosse Pointe, county of Wayne, and State of Michigan, have invented a new, original, and ornamental Design for an Automobile Hood Ornament, of which the following is a specification, reference being had to the accompanying drawing, forming part thereof, in which:

Fig. 1 is a front elevational view of an automobile hood ornament, showing my novel design;

Fig. 2 is a top plan view thereof;

Fig. 3 is a side elevational view thereof;

Fig. 4 is a cross sectional view taken on the line 4—4 of Fig. 1; and

Fig. 5 is a perspective view thereof wherein

the broken lines indicating an automobile are for illustrative purposes only.

I claim:

The ornamental design for an automobile hood ornament, substantially as shown and described.

HENRY J. KEANE.
